HARRY SWINGLEHURST, OF LACONIA, NEW HAMPSHIRE, ASSIGNEE, BY MESNE ASSIGNMENTS, TO SCOTT & WILLIAMS, INCORPORATED, A CORPORATION OF MASSACHUSETTS.

DIAL-HOLDING MECHANISM FOR KNITTING-MACHINES.

1,311,099.

Specification of Letters Patent. Patented July 22, 1919.

Application filed February 20, 1915, Serial No. 9,725. Renewed June 2, 1919. Serial No. 301,352.

To all whom it may concern:

Be it known that I, HARRY SWINGLEHURST, citizen of the United States, and resident of Laconia, in the county of Belknap and State 5 of New Hampshire, have invented certain new and useful Improvements in Dial-Holding Mechanism for Knitting-Machines, of which the following is a specification.

My invention relates to dial holding mechanism for rib knitting machines. One object of my invention is to provide mechanism applicable to rib knitting machines of an existing type for holding the needle or cam carriers of said machines stationary with 10 respect to each other, while permitting the passage of parts with respect thereto.

Other objects of my invention are to avoid the use of dogs or abutments reacting through the fabric, to provide a device capable of effective use with rib knitting machines of any size, including those of relatively large diameter, and to provide for the supply of yarn at a relatively great number of knitting waves from a source external 25 of the needle and cam carriers.

In the accompanying drawings:

Figure 1 is a vertical section through the axis of a machine of one type provided with my improved devices;

Fig. 2 is a fragmentary plan showing the dial holding arm, the movable slides for holding said arm, and means for working the slides;

Fig. 3 is a section on a line 3—3 of Fig. 1;

Fig. 4 is a detail elevation showing one of the supports for the bobbin stand and yarn guiding tubes;

Fig. 5 is a similar detail illustrating the connection to the overhead stop-motion and 40 another pair of yarn tubes;

Fig. 6 is a detail perspective of the slide operating cam;

Fig. 7 is a detail of a modified holding arm;

Fig. 8 is a detail perspective of one of the slides.

I have illustrated my invention, for one embodiment only, in connection with a rib knitting machine having a bed plate 1, and 50 an annular driven cam carrier ring 3 having bevel teeth 4 driven by a driving gear 5, said ring being provided with a cam ring 6 and cylinder needle cams 7 coöperating with

needles in a needle cylinder 8, the ring 3 rotating in a concentric bearing on bed plate 55 1, and cylinder 8 being held in a concentric seat 9 on said bed plate. Cylinder 8 is adjustable circumferentially through a short distance by means of an attached lug 10 fast on the inner face of said cylinder, which lug 60 carries set screws 11 taking against a screw 12 fast in bed plate 1. The cylinder 8 is held upon the bed plate 1 by screws 13 in enlarged bore holes 14 on the bed plate. By turning the screws 11 the cylinder may be 65 adjusted through at least one needle space.

On the carrier ring 3 posts 16 are erected, which posts carry rigidly a cross-bar or arch 17, which may have two or more arms supported at two or more points by posts 16, 70 all as usual in this type of machine.

Said arch 17 carries in a central bored boss, for adjustment by the usual set screws, a sleeve 18 which in turn carries at its lower end a dial cam cap 20 held by set screw 21. 75 Sleeve 18 provides a bearing for center spindle 25 supported against endwise movement in sleeve 18 by hardened track plates 26 having between them caged balls 27, forming a thrust bearing between the upper end of 80 sleeve 18 and the usual adjusting-nut and hand-wheel 28, which may be locked in place by set screw 29. The nut 28 is threaded on a boss 31, preferably integral with dial holding arm 30, and keyed to said center spindle 85 at 34, and held against endwise movement by washer 32 and nut 33 on the threaded and reduced upper end of said center spindle. The lower end of said center spindle 25 carries a support 36 having a flange 37 upon 90 which a needle dial 40 is held by screws 41. Support 36 is keyed to center spindle 25 at 42, and is supported upon the lower end of said center spindle by the washer and oil cup 43 and nut 44 on the reduced and 95 threaded lower end of said center spindle. It will be observed that the described structures make the arm 30 rigid with respect to the needle dial 40 and that the dial cam cap, sleeve 18, arch 17, etc., may rotate with 100 respect to said needle dial 40, center spindle 25, and arm 30. Dial cam cap 20 is held to move with arch 17 by any usual means, such as a link connected to one of the posts 16 (not shown).

The dial arch 17 carries a concentric ring

49 having integral lugs 50 equi-distant from the center of the machine, which lugs 50 are bored vertically to receive supports 52, which may be round rods as shown, fastened by 5 set screws 53 respectively in said lugs 50 and in an overhead bobbin stand 55. Said bobbin stand may be a flat or arched cast plate, having suitable openings for lightness, and bosses to receive the supports 52, and having 10 a central boss 56 for an overhead yarn-guide support 57. Pins 51 carry the yarn supply bobbins, as usual, the yarns y from said bobbins extending upward to an overhead guide (not shown) on support 57, and returning 15 downwardly through yarn eyes 58 distributed about boss 56.

The supports 52 for the bobbin stand 55 rotate in a circular path α just outside of the face of the arm 30, which face may be 20 formed as shown in Figs. 1 and 2 as an adjustable plate 60 conforming to and within the circle swept by supports 52, and attached to arm 30 by screws 61. Plate 60 may be hardened, and is provided upon its outer 25 face with recesses 63 subtending a substantial angle with respect to the center of the machine, for instance about 25°.

It will be observed that the heavy rotating mass of yarn and bobbin support is by 30 the device of the supports 52 made to rest at a number of widely separated points upon the rigid dial arch 17, posts 16, and gear ring 4. Eccentrically disposed weights on the bobbin stand, which can not be avoided, 35 are therefore supported upon a broad, firm base and can not alter or flex the center spindle or derange the relative positions of cylinder and dial during operation at speeds otherwise attainable.

40 On the bed plate 1, outside of the range of movement of the movable parts, I erect a housing 65 containing parts now to be described for holding the arm 30 stationary, while permitting passage of the supports 45 52, of structures carrying the yarns to the inclosed knitting devices, and of other connections or instruments rotating with the rotatable parts.

Means for holding the arm 30 may 50 comprise slides 75, Figs. 1, 2 and 8 moving in ways 76 in the housing 65, at fixed distances apart corresponding to the distance separating the recesses 63. A preferred form of 55 slide 75 is that shown in the drawings, a stout rectangular body a moving in a way 76, being provided with a reduced nose b to enter a recess 63, and with a surface c set at an angle, as best shown in Figs. 2, 3 and 8. For lightness, slides 75 may conveniently be 60 made as drop forgings X-shaped in cross-section, having one solid end, on which nose b is formed, and having one web cut away to leave the angular surface c , the web behind said surface being provided with 65 bosses c' .

I provide means for operating slides 75 alternately, which may be constructed as follows:

The parts c of the slides 75 each carry spaced anti-friction rolls 78, taking over the 70 periphery of a bent-disk cam 80 mounted on a short shaft 81 disposed radially of the machine, and having a bearing at 66 in the housing 65. Cam 80 is rigid with short shaft 81 and with a gear 82 fixed to the outer 75 end thereof.

Gears 83 and 84 on stud shafts 85 and 86 in said housing transmit motion to shaft 81 and cam 80, from a gear 87 carried by a short shaft 90 in a depending bearing 91 80 forming a part of housing 65, and extending under the bed plate 1. Shaft 90 is driven by a bevel gear 92 meshing with the teeth 4.

The figure of cam 80 is such as to withdraw and reinsert each of the slides 75, by 85 means of its anti-friction rolls 78, while the other slide 75 is still held in engagement with its recess 63. The angular separation of the slides 75 with respect to the center of the shaft 81 is sufficient to include between 90 said slides a withdrawing segment of said cam 80 having a dwell d and at least the angular extent of one of the inclines e and f respectively for withdrawing and reinserting slides 75 from and into contact with 95 recesses 63. Preferably the entire extent of the dwell d and inclines e and f is included between the slides; and a usual form of cam 80 will comprise two opposite withdrawing segments d, e, f occupying opposite quadrants of said cam, the other two quadrants being plane flats g serving to hold either or both of the slides 75 forward in engagement with arm 30. Rotation of the cam 80 in either direction under these circumstances 105 will first withdraw a slide 75, then hold said slide in a withdrawn position during the passage of the dwell d , and then advance said slide sharply into engagement with its recess 63, and thereafter withdraw the other 110 slide 75, holding it withdrawn during the same interval of time as the first actuated slide. The upper surface of the cam 80

moves at a constant rate related to the rate 115 of ring 3, and the rate of passage of supports 52 and the other parts which are to be passed through the connection formed between the arm 30 and the housing 65, the slide 75 at the bottom of Fig. 2, for instance, being thus first moved, to open the passage 120 at α for the attachments of the rotating member of the machine moving in the direction of the arrow on said figure. The movement of the cam 80 is so timed by the gear train 82, 83, 84, 87 as to secure the 125 closure of the first opened slide behind the rotating element before the complete opening of the second slide by the passage of a second withdrawing portion d, e, f of cam 80.

It will be seen that the frequency of the 130

opening and closing of the slides 75 will depend upon the ratio of movement between the ring 3 and gear teeth 4 and the gear 82. The teeth 4 being relatively of great extent, it will be obvious that the operation of the slides 75 may be repeated as many times as desired during one complete revolution of the machine. I have shown in the drawings, by way of example only, a dial arch 17 carrying four lugs 50 on the ring 49, each of said lugs carrying a support 52, except one mentioned below, and each of said lugs also marking the location of removable yarn tubes 62, arbitrarily shown as two in number, through which tubes yarns y are conducted to yarn feed guides 100 carried by the dial cam cap 20; for instance to supply eight knitting waves, with single or four waves with double yarns. The machine illustrated is intended to be employed with cams for four knitting waves, but it will be understood that for a greater number, lugs 50, supports 52 and yarn tubes 62 may be provided at any desired parts of ring 49, and that each lug and support 52 may carry any desired number of yarn-tubes 62.

A preferred form of yarn tube and support is shown in Figs. 4 and 5, support 52 carrying a clamp-bracket 54, bored for removable tubes 62, held by set-screws 59, permitting a tube 62 to be taken out for cleaning without disturbing any other parts.

Whatever the number of yarn tubes employed, their extent along the periphery of the circular path α defined by them will be sufficiently small to enable the first slide 75 to be opened for their passage, and closed behind them before the second slide 75 is actuated. In the arrangement shown the slides 75 are actuated eight times during each revolution of the carrier 3.

Such other connections as may be desired between the overhead part of the machine and the rotating cam carriers may be accommodated in the circular path α at the position of the lugs 50; as one instance, one of the lugs 50 (see Figs. 1 and 5) may carry a rigid tube 102 in which is journaled a vertical rock-shaft 103 having cranks 104 and 105, to serve as a connection between a rock-shaft 106 and crank 107 forming a part of an overhead yarn-break detecting stop-motion mechanism of any desired type and a detector finger 107 for operating a power let off device such as ring 108, corresponding to the disclosure of Letters Patent to Scott & Swinglehurst, No. 679,641, dated July 30, 1901.

It will be observed that the strain taken by the arms 30 and the slides 75 is merely that of resistance to operative movement of the dial needles held in the needle dial 40; that said parts are relatively stationary in the preferred arrangement shown; and that there is no momentum of parts under rapid

movement to be resisted by the device, inertia aiding the slides 75 to hold the dial stationary. The parts actually moved to permit the passage of the desired rotating elements are relatively small and light, and their rapid actuation is effected without shock or jar to the machine, and I find in practice that the positioning of the needle dial may be very accurately maintained by the said devices.

For determining in the first instance the angular position of the dial needles with respect to the cylinder needles, I may adjust the plate 60 on the arm 30 by means of the screws 61, but I prefer in most cases to rotate the needle cylinder 8 as by means of the screws 11 reacting with the screw 12 to bring the cylinder needles into the proper relation with the dial needles.

It will be understood that changes may be made in the devices illustrated within the scope of my invention. For instance, I have shown in Fig. 7 a modified dial-holding arm 111 for replacement of arm 30, said arm 111 having parallel lugs 112 with faces 115 and 116 to receive hardened plates 113 held by screws 114. By mounting both plates on faces 116, or one on a face 116 and another on face 115, or by mounting both said plates on the exterior faces, different angles may be subtended by them without change of the standard parts, to engage with slides 75 having noses b at corresponding distances, and to alter the angular position of the points of opening and closing the sides to agree with connections mounted on ring 49 at varied angles. The construction of slides 75 enables the engaging faces b of noses b to be formed at any part of the width of said slides, thereby to vary the spacing of said faces, and by so changing the form of slides 75, and the length, thickness and position of plates 113, existing machines may be equipped with my new devices through wide variations in diameter, number of feed-points and other characteristics.

It will be understood that for changes in the period of operation of cam 80 and slides 75, I may employ gearing of any desired ratio in housing 65. For simplicity, I prefer the construction shown, studs 85 and 86 being mounted in holes drilled to suit the selected gear train, the face and top of the housing being covered by plates 110, which may have suitable finished bosses 120 to hold said gears 83 and 84 in place, the construction providing a noise- and oil-tight casing, but any suitable change-gear construction may be employed. Gear 92 may have a separate cover 121.

The housing 65 may be erected at any convenient point about the bed plate, but I prefer to place it at the back of the machine, about 45° from the driving shaft, where it will be out of the way of the operator.

What I claim is:

1. A circular knitting machine having in combination a pair of needle carriers, a pair of cam carriers, means to cause relative rotation between said pairs of carriers, and means to hold the carriers of one pair relatively fixed to each other comprising movable slides, a mounting therefor fixed to one of said carriers, an abutment fast to 10 the other carrier, rotary means for moving said slides out of and into contact with said abutment and devices for rotating said rotary means a plurality of times during each relative rotation of said carriers.

15 2. A circular knitting machine having in combination a pair of needle carriers, a pair of cam carriers, means to cause relative rotation between said pairs of carriers, and means to hold the carriers of one pair relatively fixed to each other comprising alternately operating slides, a mounting therefor fixed to one of said carriers, a cam for moving said slides in succession out of and into contact with an attachment of the other 25 carrier, and means for rotating said cam a plurality of times during each relative rotation of said carriers.

3. A knitting machine having in combination a pair of needle carriers, a pair of cam carriers, means to rotate one pair of said carriers with respect to the other pair, means for rotating one pair of said carriers together, and means to hold the other carriers in fixed relation comprising slides, a 35 cam for withdrawing and reinserting said slides in succession, an abutment fast to one carrier for engagement by said slides, and means for rotating said cam a plurality of times during each revolution of said rotary 40 carriers.

4. A circular knitting machine having in combination a pair of needle carriers, a pair of cam carriers, means to cause rotation of the cam carriers, yarn supply means rotating 45 with the rotating carriers, and means to hold the needle carriers relatively fixed to each other comprising alternately operating slides, a mounting therefor fixed to one of said needle carriers and a cam for moving said slides 50 alternately into and out of contact with an attachment of the other needle carrier, and means for rotating said cam a plurality of times during each relative rotation of said carriers, whereby to pass a plurality of 55 yarns leading from the rotating yarn supply means to a rotating cam carrier.

5. A knitting machine having in combination two needle carriers, two cam carriers, means to rotate one pair of said carriers with respect to the other pair, means connecting said rotary carriers for rotation together, and means to hold the other carriers in fixed relation comprising slides, a cam for withdrawing and reinserting said 60 slides in succession and means for rotating 65

said cam on an axis fixed with respect to one of said carriers and at an angle thereto, and an abutment fast to the other carrier for engagement by said slides.

6. A knitting machine having in combination two needle carriers, two cam carriers, means to rotate one pair of said carriers with respect to the other pair, means connecting said rotary carriers for rotation together, and means to hold the other carriers in fixed relation comprising alternately operating slides fixed with respect to one of said carriers, a cam for operating said slides and means for rotating said cam on an axis parallel with said slides, and an abutment fast to the other carrier for engagement by said slides.

7. A rib knitting machine having elements such as a needle carrier and needles in an internal position with respect both to the fabric produced and to other fixed elements of the machine, such as another needle carrier and needles coöperating to produce the fabric; knitting cams rotating externally of said elements, rotary yarn supply means, and means to drive said means, in combination with means for holding said internal element in fixed relation to said other fixed elements including an abutment thereon, a plurality of slides, and rotating means to free said slides in turn from said abutment driven at a constant rate greater than that of said knitting means, whereby a plurality of connections rotating with said knitting cams may pass between said slides and said abutment.

8. A rib knitting machine having a needle cylinder and needle dial, cam carriers for cylinder and dial cams, driving means for said cam carriers, a rotary bobbin stand and supports therefor carried by one of said cam carriers, in combination with means to hold the said cylinder and dial in a fixed relation to each other comprising an arm rigid with said dial, slides taking against said arm, a mounting for said slides fixed relatively to said cylinder, a cam on said mounting for moving said slides alternately into and out of contact with said arm, and gearing for rotating said cam to withdraw and reinsert 110 said slides in turn at the passage of each of said supports.

9. A rib knitting machine having in combination a needle cylinder and needle dial, cam carriers for cylinder and dial cams, driving means for said cam carriers, a bobbin-stand, a plurality of supports on one of said cam carriers equidistant from the center thereof for holding and driving said bobbin-stand and means to hold the said cylinder and dial in a fixed relation to each other comprising means rigid with said dial within the path swept by said supports, slides movable across said path into contact with said means, means for moving said 120 125 130

slides successively out of said path during the passage of each of said supports, and for returning one of said slides before moving another.

- 5 10. A circular knitting machine having in combination needle carriers, cam carriers and a bobbin support, a plurality of means connecting the bobbin support to a cam carrier for support thereby and movement therewith, means to drive said cam carrier and bobbin support, and means to hold said needle carriers fixed with respect to each other comprising slides, a mounting therefor fixed with respect to the one of said carriers, and means to move said slides in succession out of and into the path of said connecting means and into and out of contact with an attachment of the other carrier, comprising a cam on said fixed mounting 15 20. and means driven from said cam carrier to rotate said cam once for each passage of one of said connecting means.

11. Dial holding means for a rib knitting machine having in combination a needle dial, an arm rigid therewith, recesses in said arm, slides for engaging said recesses, a housing on a fixed part of said machine having ways for said slides, a shaft in said housing, a cam for moving said slides alternately 25 30 into and out of contact with their recesses mounted on said shaft, and gearing between said shaft and a rotary element of said machine.

12. A rib knitting machine having a cylinder, a dial, a cylinder cam ring and a dial cam cap rotating with respect to said cylinder and dial, and means for holding said dial relatively fixed with respect to said cylinder, said means comprising devices for 35 40 opening a path concentric with said cam ring at a predetermined plurality of sep-

arate points in the circumference thereof, an overhead yarn supply mechanism and stop-motion device rotating with the rotary part of the machine, and a connection from 45 said stop-motion to a power let-off device in said path at one of said circumferential points.

13. A dial holding attachment for rib knitting machines comprising a housing for 50 erection on a fixed part of the machine, ways in said housing for dial holding slides, a rotary cam for withdrawing said slides in turn, and means in said housing for rotating said cam from a moving part of said 55 machine.

14. A dial holding attachment for rib knitting machines having a driven cam-ring comprising a housing for erection on a fixed part of the machine, ways in said housing 60 for dial holding slides, a rotary cam for withdrawing said slides in turn, a gear train in said housing, a driving shaft therefor, and a gear on said shaft for engagement with the driving means for said cam-ring. 65

15. A rib knitting machine having a dial, and a holding device for said dial comprising an arm fixed to said dial, a plurality of slides for engaging said arm and means for withdrawing said slides comprising a cam 70 mounted on an axis parallel to the direction of motion of one of said slides, means on said slides engaging said cam and means for rotating said cam.

In testimony whereof, I have signed my 75 name to this specification in the presence of two subscribing witnesses.

HARRY SWINGLEHURST.
